ABSTRACT: The novel means for dyeing human hair according to the invention are based on oxidation dyes and comprise heterocyclic amino compounds and suitable coupling components. For example, 2 parts of 6-aminotetrahydroquinoline hydrochloride, 1 part of α -naphthol, 1 part of hydrogen peroxide are mixed with 96 parts of water and adjusted to a pH of 9.5. By treating gray human hair with the resulting solution a dark blue coloration is obtained.

The hair dyes according to the invention have, in addition to other favorable characteristics, the advantage of being easily removable from the hair, e.g., by reducing agents.

**DYEING HUMAN HAIR WITH OXIDATION DYES
COMPRISING HETERO CYCLIC AMINO COMPOUNDS**

This invention relates to agents for dyeing human hair by means of oxidation dyes, particularly by means of heterocyclic amino compounds.

It has been known to use for dyeing human hair oxidation dyes which contain as the dye component phenylene diamines. It has also been suggested to use for these purposes diaminopyridines. The before-mentioned compounds are converted by oxidation with atmospheric oxygen, or especially by the addition of chemical oxidizing agents, such as hydrogen peroxide, on the hair into the dyes. However, these hair dyes have, among others, the disadvantage that their removal from the hair is difficult.

It has now been found that the hair dyes according to the present invention described hereinafter do not exhibit this disadvantage and—in addition to other advantages—can be easily removed from the hair. The novel agents according to this invention are characterized by a content of

a. heterocyclic amino compounds corresponding to the general formula (I):

X stands for the atoms necessary for the formation of a heterocyclic, nonaromatic, five-membered ring, or six-membered ring; as well as

b. coupling components known by themselves for hair dyes, on the basis of aromatic compounds containing amino groups or hydroxyl groups, or hydroxyl and amino groups, or pyrazolones, or aroyl derivatives, or acylacetic acid derivatives.

In carrying out the invention, it is preferred to use compounds, in which in the heterocyclic amino compound corresponding to the formula (I), the radical or group R₁ is an aliphatic radical having not more than 10 carbon atoms, especially an alkyl group or a hydroxy-alkyl group having in each case one-four carbon atoms. Said alkyl group may be rectilinear or branched.

Substituents of the first order—described above for the symbol R₂ of the heterocyclic amino compounds of the formula (I)—are, for example, the following: halogen atoms, especially chlorine or bromine atoms, rectilinear or branched alkyl groups containing one-four carbon atoms, substituted alkyl groups of said chain length, such as, for example, hydroxy-alkyl groups or aminoalkyl groups, and also amino groups, amino groups substituted by alkyl radicals or alkanol radicals and also hydroxyl groups substituted by alkyl groups, such as —OCH₃ or —OC₂H₅.

The formation of a heterocyclic, nonaromatic five-membered ring or six-membered ring, can be brought about in different ways. According to a preferred embodiment, heterocyclic amino compounds corresponding to the above formula (I) can be used in which X stands for one of the groups —aminoindolenine; (CHphd 2)₃—, —CH₂—CH₂—, —CH₂—CH(CH₃)—, —NR—CH₂—CH₂—, —CH₂—NR—CH₂—, —O—CH₂—CH₂; (R being H or an alkyl group having one to four carbon atoms). Further examples are amino compounds corresponding to the formula (I) in which X stands for the group —CO—NH— or —NH—CO—CH₂—. As individual compounds, especially the following can be considered: 6-aminotetrahydroquinoline; 1-methyl-6-aminotetrahydroquinoline; 1-methyl-6,8-diaminotetrahydroquinoline; 1-methyl-6-amino-8-methoxytetrahydroquinoline; 1-ethyl-6-aminotetrahydroquinoline; 1-(β -hydroxyethyl)-6-aminotetrahydroquinoline; 4-methyl-7-aminodihydrobenzoxazine (1,4); 1-(β -hydroxyethyl)-2-methyl-5-aminoindolenine; 2-methyl-5-aminoindolenine; 5-aminoundazolone-3; 7-amino-2-oxo-tetrahydroquinoxaline; 6-aminotetrahydroquinoxaline. Preparation of the amino compounds used is carried out according to generally known methods, for example, by in-

troduction of the amino group into the corresponding heterocyclic compounds.

Known coupling components on the basis of aromatic compounds containing amino groups or hydroxyl groups, are, by way of example, diamines, phenols, naphthols, polyphenols and aminophenols. In the case of diamines, aminophenols and phenols, preferably the ortho- or meta-compounds are used. As examples of suitable individual compounds, the following are mentioned:

10	m-phenylenediamine o-phenylenediamine m-aminophenol o-anisidine 2,4-diaminoanisole o-toluylenediamine m-toluylenediamine 2,4-diaminophenol o-aminophenol	pyrogallol resorcinol pyrocatechol aminoresorcinol 1,5-dihydroxynaphthalene 1,5-aminohydroxynaphthalene 1,8-aminohydroxynaphthalene α -naphthol

20 Furthermore pyrazolones and also aroyl-derivatives or acylacetic acid derivatives come into consideration, for example

25	3-methylpyrazolone-(5) 1-phenyl-3-methylpyrazolone-(5) 1,3dimethylpyrazolone-(5)

30	3-aminopyrazolone-5 acetocrylic acid anilide benzoylacetanilide benzoylacettoluidide nicotinoylacetanilide.

35 The coupling components are used appropriately in about molecular quantities with relation to the heterocyclic amino-compounds. However, it is, in general, not detrimental if the latter are used in a certain excess. In some cases it has been found expedient to apply the heterocyclic amino compounds of the above-described type in the form of salts with strong organic or inorganic acids, such as oxalic acid, maleic acid, sulfuric acid and hydrochloric acid. The use of the easily accessible hydrochlorides is preferred.

40 As in the case of other oxidation dyes, the color can be developed by atmospheric oxygen, as well as particularly by chemical oxidizing agents, e.g., preferably hydrogen peroxide and its addition compounds especially with urea, melamine, and sodium borate. Dyeing of the hair is carried out in the temperature range of 15°–40° C., preferably at ordinary room temperature. The hair dyes can be applied in the form of aqueous solutions, particularly however in form of a cream or emulsion. For this purpose the dye components are mixed with any tensides, particularly anionic or nonionogenic tensides. Examples of tensides are especially alkylbenzenesulfonates, fatty alcohol sulfates, alkylsulfonates, fatty acid ethanolamides, addition products of ethyleneoxide to fatty alcohols and alkylphenols.

55 The absorptive power of the above-named dyes is good, even in mixture with such additions. Therefore, the hair dyes can be produced in the form of shampoos, particularly cream-like shampoos which are frequently demanded in practice.

60 Furthermore, to the products according to the invention thickening agents, such as methylcellulose, starch, higher fatty alcohols, Vaseline (petrolatum), paraffin oil, and fatty acids, and also perfume oils or substances for the care of the hair, e.g. pantothentic acid and cholesterol may be admixed.

65 Thereby, the admixed material is applied in proportions which are conventional for the respective purpose. Wetting agents can be used especially in proportions of 0.5–30 percent by weight calculated on the total composition. Thickening agents are added in proportions of 0.1–25 percent by weight based on the weight of the total composition. Concentration of the dyes amounts—in dependence on the intended use—up to 5 percent, preferably, however, to 0.1–2 percent by weight, likewise based on the total composition.

70 The hair dyes according to this invention can be used at a weakly acid, neutral or especially alkaline pH range. The dye-

ing obtained with the hair dyes described herein have good characteristics relative to the effect of light, washing and rubbing and—in contrast to conventional products based on oxidation dyes—can be easily removed with reducing agents, such as sodium-hydroxymethanesulfinate.

EXAMPLE 1

Two parts by weight of 6-aminotetrahydroquinoline hydrochloride, 1 part by weight of α -naphthol and 1 part by weight of hydrogen peroxide are mixed with 96 parts water and adjusted to a pH value of 9.5 with ammonia. Gray human hair is treated with this solution for 20 minutes at 15° C. A deep dark blue coloration is thus obtained.

EXAMPLE 2

A dyeing cream is prepared in the following manner: 1 part by weight of 1-(β -hydroxyethyl)-6-aminotetrahydroquinoline hydrochloride and 1 part by weight of 3-aminopyrazolone-5, are dissolved in an emulsion consisting of 10 parts by weight of fat alcohols having chain lengths of 16-18 carbon atoms, 10 parts by weight of fatty alcohol sulfate based on coconut oil and 70 parts of water and adjusted with ammonia to a pH value of 9. The resulting solution is mixed with 1 part of hydrogen peroxide and filled up with water to 100 parts by weight. If gray hair is treated with this dyeing cream thus prepared at 20° C., for 20 minutes, a red-violet coloration is obtained.

EXAMPLE 3

Dyeing creams, as described in the above example 2, have been prepared, in which, however, as the developer component and the coupling component the compounds stated in the following table were used.

The coloration stated in the right column of said table were obtained by treating gray human hair with the respective creams at 20° C. for 20 minutes.

Equal results are obtained if the heterocyclic amino compounds used and identified in said table as the developer component, are applied in form of the corresponding salts with oxalic acid, maleic acid, sulfuric acid or hydrochloric acid respectively.

TABLE			
No.	Heterocyclic amino compound	Coupling Components	Coloration
1	1-methyl-6-amino-tetrahydroquinoline	2,4-diamino-toluene	gray-green
2	1-methyl-6-amino-tetrahydroquinoline	resorcinol	violet-brown
3	6-aminotetrahydroquinoline	2,4-diamino-anisole	dark-blue
4	1-ethyl-6-amino-tetrahydroquinoline	α -naphthol	dark-blue
5	1-(β -hydroxyethyl)-6-aminotetrahydroquinoline	2,4-diamino-toluene	blue-green
6	4-methyl-7-amino-dihydrobenzoxazine-(1,4)	α -naphthol	dark-blue
7	1-(β -hydroxyethyl)-2-methyl-5-amino-indolenine	α -naphthol	dark-blue
8	2-methyl-5-amino-indolenine	α -naphthol	weakly gray
9	5-aminoindazolone-3	α -naphthol	weakly gray
10	7-amino-2-oxo-tetrahydroquinoxaline	α -naphthol	weakly yellow
11	6-aminotetrahydroquinoxaline	resorcinol	yellow
12	1-methyl-6,8-diamino-tetrahydroquinoline	α -naphthol	brown
13	1-methyl-6-amino-8-methoxytetrahydroquinoline	resorcinol	dark ash-blond
14	1-ethyl-6-amino-tetrahydroquinoline	benzoylacetanilide	yellow
15	1-(β -hydroxyethyl)-	1-phenyl-3-	purple

16	-6-aminotetrahydroquinoline 1-(β -hydroxyethyl)-2-methyl-5-amino-indolenine	methyl-pyrazolone-5 acetoacetic acidanilide	yellowish

The term "substituents of the first order" is used herein to denote substituents which direct further groups, i.e. nitro-groups, predominately into the o- or p-position on an aromatic nucleus.

10 The generally known methods suggested for the preparation of amino compounds used in carrying out the invention, are described, for example: Weissberger et al., J. Amer. Chem. Soc. 73, 3,100 (1951); Skikoma, J. Chem. Soc. 119, 744; Knuppel, Liebigs Ann. d. Chem. 310, 72 (1899). The excess of the heterocyclic amino compound described above may amount to 3 to 1 mole, based on 1 mol of the coupling compound used.

15 The term "room temperature" is used herein to denote about 18° to 25° C., and the term "tensides" is used to denote and include surfactants like alkylbenzenesulfonates (alkyl group C₈-C₁₅), fatty alcohol sulfates (C₁₂-C₂₀), alkylsulfonates (C₁₂-C₂₀), fatty acid ethanolamides (alkyl group C₁₁-C₁₉), addition products of ethylene oxide to fatty alcohols (C₁₂-C₂₀) and alkylphenols (alkyl group C₈-C₁₂).

20 25 The weakly acid, neutral and alkaline pH values preferred in carrying out the invention are in the range from 3 to 10.

The hydrogen peroxide used according to the above examples refers to hydrogen peroxide of 100 percent concentration.

30 35 The recitation "atoms necessary for forming a heterocyclic nonaromatic five-membered (or six-membered) ring" means radicals, comprising for example —(CH₂)₂—, —(CH₂)₃—, —(CH₂—CH(CH₃)—, —NR—CH₂—CH₂—, —CH₂—NR—CH₂—, —O—CH₂—CH₂—, (R being H or alkyl group having one-four carbon atoms).

To the dyeing creams used in carrying out the invention conventional amounts of wetting agents and/or washing agents may be added. Suitable examples are 0.5-30 percent by weight of alkylbenzene sulfonates, fatty alcohol sulfates, alkylsulfonates, fatty acid ethanolamides, addition products of ethylene oxide to fatty alcohols and alkylphenols.

The parts and percent mentioned herein are by weight if not otherwise stated.

45 50 What is claimed is:
1. A process for the dyeing of human hair which consists essentially of applying to said hair at temperatures ranging substantially from 15° to 40° C. and for a time sufficient to effect dyeing, an effective amount of an aqueous solution containing from 0.1 to 5 percent by weight of a mixture of a coupling component and a developer component in a mole ratio of 1:1 to 1:3 said coupling component being selected from the group consisting of aromatic diamines, phenols, naphthols, aminophenols, 3-methylpyrazolone-(5), 1-phenyl-3-methylpyrazolone-(5), 1,3-dimethylpyrazolone-(5), 3-aminopyrazolone-(5), acetoacetic acid anilide, benzoylacetanilide, benzoylacetyluidide and nicotinoylacetanilide and said developer component being selected from the group consisting of (1) a heterocyclic amino compound of the formula

55 60 65 wherein R₁ is a member selected from the group consisting of hydrogen, alkyl having one to four carbon atoms and hydroxylalkyl having one to four carbon atoms, R₂ is a member selected from the group consisting of hydrogen, amino, methoxy and ethoxy and X represents a bivalent linkage selected from the group consisting of —CH₂—CH₂—CH₂—, —CH₂—CH₂—, —CH₂—CH(CH₃)—, —NR—CH₂—CH₂—, —O—CH₂—CH₂—, —CO—NH— and —NH—CO—CH₂—; 70 75 where R represents a member selected from the group consisting of hydrogen and alkyl having one to four carbon atoms, and (2) its acid addition salt with a strong acid selected from the group consisting of inorganic and organic acids.

2. The process of claim 1 wherein said heterocyclic amino compound is in the form of an acid addition salt of a strong acid selected from the group consisting of inorganic and organic acids.

3. The process of claim 1 wherein said aqueous solution has a further content of from 0.5 to 30 percent by weight of an agent selected from the group consisting of alkylbenzene sulfonates, fatty alcohol sulfates, alkylsulfonates, fatty acid ethanalamides, ethylene oxide adducts of fatty alcohols and ethylene oxide adducts of alkylphenols.

4. The process of claim 1 wherein said aqueous solution has a further content of a chemical oxidizing agent.

5. The process of claim 1 wherein said heterocyclic amino compound is selected from the group consisting of 6-amino-tetrahydroquinoline, 1-ethyl-6-aminotetrahydroquinoline, 1-(β -hydroxyethyl)-6-aminotetrahydroquinoline, 4-methyl-7-aminodihydrobenzoazine-(1,4), 1-(β -hydroxyethyl)-2-methyl-5-aminoindolenine, 2-methyl-5-aminoindolenine, 5-aminoindazolone-3,7-amino-2-oxo-tetrahydroquinoxaline, 6-aminotetrahydroquinoxaline, 1-methyl-6,8-diaminotetrahydroquinoline diaminotetrahydroquinoline and 1-methyl-6-amino-8-methoxytetrahydroquinoline.
